INVENTOR.
Paul R. Hahnemann:

BY

Stuckert
ATTORNEY.

UNITED STATES PATENT OFFICE.

PAUL R. HAHNEMANN, OF SOUTHBURG, CONNECTICUT, ASSIGNOR TO THE PECK, STOW & WILCOX COMPANY, OF SOUTHBURG, CONNECTICUT, A CORPORATION OF CONNECTICUT.

METAL-WORKING TOOL.

1,322,109.

Specification of Letters Patent. Patented Nov. 18, 1919.

Application filed May 17, 1918. Serial No. 235,065.

To all whom it may concern:

Be it known that I, PAUL R. HAHNEMANN, a citizen of the United States, and a resident of Southburg, in the county of Hartford, State of Connecticut, have invented certain new and useful Improvements in Metal-Working Tools, of which the following is a specification.

The invention relates particularly to hand tools for use in the working of sheet metal—for instance tools adapted for the crimping, beading, flanging, etc., of sheet metal. The invention is illustrated as embodied in a corrugating tool, such as tinsmiths use in properly shaping the end of a stove pipe, and the description of the invention will be directed to the embodiment here illustrated. I desire it to be understood however that the invention is not limited to the precise embodiment here shown.

The object of this invention is to provide a tool of the character described having features of novelty and advantage.

In the drawings—

25 Figure 1 is a view showing the method of holding the tool, the handle being shown in section.

Fig. 2 is the plan view of the tool.

Fig. 3 is a side view of the tool.

30 Fig. 4 is a central section showing the tool in position reverse from that of Fig. 3.

Fig. 5 is a detail view of a portion of the tool looking from the front of Fig. 2.

Referring to the drawings—*a*, denotes the 35 hand grip of the tool having rearwardly extending arms *b*, *b*, and a cross bar *c*, which by preference is dropped a little below the plane of the arms *b*, *b*. The hand grip is bored to receive the shaft 5, operated by

40 the crank 6, and carrying at its opposite end one of the crimping rolls 7. Fig. 1 shows the manner of use of this tool and the support which is provided for the frame by having the cross bar *c*, underlie the wrist,

45 acting as a brace or steady rest to support the frame against the tendency to twist when the shaft is turned. This style of frame and holding means permit of using a crank handle for operating the crimping

50 rolls which makes it possible to operate the tool at a very rapid rate.

The complementary crimping roll 10, is mounted on a short stud shaft 11, which is mounted on a carriage 12, pivoted in the

frame as at 13, at one side of the axis of 55 the main shaft 5, and having a forwardly projecting ear 14, from which the adjusting screw 15 operates to adjust the position of the carriage and the spacing of the crimping rolls from one another. It will 60 be seen that in the adjustment of the crimping roll 10, its axis always remains parallel with the main axis 5, thus insuring that the two rolls will be alined at all times while the metal to be operated on is fed 65 through the rolls. 20 is a guide plate on the frame against which the edge of the metal being operated on may have a bearing.

In accordance with the provisions of the 70 patent statutes I have described the principle of operation of my invention, together with the structure which I now consider to represent the best embodiment thereof; but I desire to have it understood that the structure here shown is only illustrative, and that the invention can be carried out by other means.

I claim as my invention:—

1. In a tool of the character described, a 80 hand grip, a brace connected therewith and adapted for engagement with the extremity of the operator holding the tool, a rotary shaft supported by said hand grip, means for rotating said shaft, coöperating metal 85 fabricating members, one of which is mounted upon an axis parallel with the axis of said shaft and a driving connection between said shaft and members.

2. In a tool of the character described, a 90 hand grip, a brace connected therewith and adapted for engagement with the extremity of the operator holding the tool, a straight rotary shaft supported by said hand grip, means on one end of the shaft for rotating 95 the same, and a metal fabricating member on the other end of said shaft.

3. In a tool of the character described, a hand grip, a brace connected therewith and adapted for engagement with the extremity 100 of the operator holding the tool, a rotary shaft supported by said hand grip, means for rotating said shaft, metal working rolls, and a driving connection between said shaft and one of said rolls.

4. In a tool of the character described, a rotary shaft, means for rotating the shaft, metal working rolls, a driving connection

between said shaft and one of said rolls, a hand grip supporting said shaft and located between the means for rotating the shaft and the metal working rolls, and a brace connected to the hand grip and adapted for engagement with the extremity of the operator holding the tool.

5. In a tool of the character described, a frame comprising a hand grip, a cross bar at the rear of and supported by said hand grip and adapted for engagement with the extremity of the operator holding the tool, a rotary shaft supported by and extending lengthwise of said hand grip, a crank arm at one end of said shaft, metal working rolls, and a driving connection between said shaft and one of said rolls.

10. In a tool of the character described, a frame comprising a hand grip, arms extending rearwardly from said grip and a cross bar between said arms and below the plane

thereof; a rotary shaft supported by and extending longitudinally of said hand grip; a crank arm at one end of said shaft; metal working rolls; and a driving connection between said shaft and said metal working rolls.

15. In a tool of the character described, a rotary shaft, means on one end of the shaft for rotating the same, a metal fabricating member on the other end of said shaft, a hand grip supporting said shaft and located between said means for rotating the shaft and said fabricating member, and a brace connected to the hand grip and adapted for engagement with the extremity of the operator holding the tool.

20. PAUL R. HAHNEMANN.
